CLAIM

The ornamental design for an hood lockdown cap, as shown and described.

DESCRIPTION

FIG. 1 is a top, right perspective view of a hood lockdown cap showing my new design thereof;

FIG. 2 is a top plan view thereof;

FIG. 3 is a side left elevational view thereof;

FIG. 4 is a front elevational view thereof; and,

FIG. 5 is a bottom plan view thereof.

In the drawings, the broken lines depict environmental subject matter only and form no part of the claimed design.
